UNITED STATES PATENT OFFICE.

JOHN E. GRIFEN, OF MCGUIRE, MISSOURI.

HALTER.

No. 911,232.

Specification of Letters Patent.

Patented Feb. 2, 1909.

Application filed September 8, 1908. Serial No. 452,018.

To all whom it may concern:

Be it known that I, JOHN E. GRIFEN, a citizen of the United States, residing at McGuire, in the county of Dunklin and State of Missouri, have invented a new and useful Halter, of which the following is a specification.

This invention relates to halters, and has for its object to provide a simple, cheap and universal halter for various animals, made of a single strap without buckles and capable of being adjusted to fit different sizes and shapes of heads and the heads of different kinds of animals. Besides being economically made, the material may be of a more or less cheap nature such as leather, webbing, rope, etc.

The application of this halter to the head of an animal is very simple and facile, and when properly adjusted it does not worry nor irritate the animal, nor can the animal escape therefrom.

With these and other objects in view the invention consists of the construction, combination and arrangement of parts herein-after described and claimed and illustrated in the accompanying drawing which represents a perspective view of the halter applied, the head of the animal being shown by dotted lines.

In the drawing, 1 and 2 indicate two flat, substantially square metal plates, through each of which and close to each corner is made an opening 3, which openings in the present case are elongated slots for the passage of a continuous strip of leather 4 or webbing, or the openings may be round when a rope is used. The two oppositely disposed slots 3 in each plate are parallel to each other and perpendicular to the other two slots in the same plate. To prevent danger, the pointed corners of the plates 1 and 2 are removed.

To assemble the parts, each end of the strip or webbing 4 is passed horizontally through the two vertical slots 3 in a plate from within outwardly and then inwardly again. After which the plates 1 and 2 are slid towards the center of the strap 4 to form between them the nose band or loop 5 of such size as to pass loosely around the front of the nose when the plates 1 and 2 are about midway of the muzzle of the animal.

From the plates 1 and 2 the ends of the

strip 4 are carried rearwardly and towards each other sufficiently far to pass loosely through a ring 6 back of the cheeks and below the neck of an animal, thence upwardly as at 7 through a sliding loop 8 and downwardly on the opposite sides of the halter to the cheek plates 1 and 2, passing outwardly through the upper horizontal slots 3 and thence between the cheek plates and the horizontal strips 4 and back to the inner side of said cheek plates through slots at the bottom thereof.

The cheek plates are fastened to those parts of the strip 4 which pass thereover by punching holes 9 in the cheek plates from the inside to throw up a bur to hold the strip, as shown by the cheek plate 2, or by other suitable means.

From the above it will be noted that the halter may be shortened by drawing the parts 7 of the strip 4 through the sliding loop 8 to raise the cheek plates, and lengthened by an opposite movement of strip. The fastening rope, strap or chain is linked to the ring 6 and the greater the draft thereon the more secure will the halter be retained on the animal.

What is claimed is:—

1. An adjustable halter made of a single strip of flexible material crossing itself at different points, a cheek plate on each side of said halter to which the ends of said strip are secured and through openings in which the nose band or loop passes, means at the other crossing point through which the strip is adapted to slide, and a ring connecting two portions of said strip and slidable thereon.

2. An adjustable halter made of a single strip of folded flexible material crossing itself at different points, a cheek plate on each side of said halter, a pair of oppositely disposed openings in said cheek plates through which the ends of the strip pass, a second pair of openings disposed at right angles to the first pair through which a portion of said strip passes, means at the upper end of said halter through which crossed portions of said strip may slide at will and a loose ring slidable on two non-crossed portions of said strip.

3. A halter made of a single piece of flexible material bent into U-shape to form a nose-band, and having its terminals carried rearward into close proximity to each other, thence convexed from each other and carried

upward, crossing each other, thence downward, crossing the nose-band; means for uniting the terminals with the nose-band; a sliding connection inclosing the terminals at 5 their intersection; a second sliding connection inclosing the terminals below their intersection and at their point of proximity.

In testimony that I claim the foregoing as my own, I have hereto affixed my signature in the presence of two witnesses.

JOHN E. GRIFEN.
